UNITED STATES PATENT OFFICE.

CLIFFORD J. ZWICKEY, OF NORTH ST. PAUL, MINNESOTA.

SPORT CAR.

Application filed July 11, 1921. Serial No. 483,799.

To all whom it may concern:

Be it known that I, CLIFFORD J. ZWICKEY, a citizen of the United States, residing at North St. Paul, in the county of Ramsey 5 and State of Minnesota, have invented certain new and useful Improvements in Sport Cars, of which the following is a specification.

This invention relates to sport vehicles, 10 and more particularly to the class including automobiles provided with boat bodies, so that the device may be used as a conveyance either on land or water.

An object of the present invention is the 15 provision of a combination sport car and boat, having provision for readily swinging the wheels into out of use position during travel, from the driver's position, to bring the boat body into play.

20 A further object of the invention is to provide a sport car of the class described, the general construction thereof being after the nature of the fuselage of an aeroplane, that is to say, a light but substantial wood 25 or metal frame work, sufficiently stiff to support a motor and withstand the vibrations thereof, and suitably walled-in after the manner of ordinary canoes to render the body serviceable as a boat, the device 30 being propelled jointly by an aeroplane propeller and power driven traction wheels.

Other objects of the invention will be pointed out throughout the specification, the invention consisting in the construction, 35 combination and arrangement of parts illustrated in the accompanying drawings and hereinafter specifically claimed.

In the drawings:

Figure 1 is a side elevation of my improved sport car.

Figure 2 is a plan view of same, parts having been removed to expose the mechanism within the car body.

Figure 3 is a fragmentary semi-diagrammatic perspective view of the car body, a part of the wheel raising mechanism and steering post being shown in dotted lines, and the operating cable system being shown in full lines.

50 Figure 4 is a fragmentary perspective view of the front axle illustrating the manner of swinging same to raise the front wheels.

Figure 5 is fragmentary perspective view 55 of the steering post, showing the mechanism whereby it is operatively connected with

the rudder to control it, and with the knuckles of the front wheels to control the latter.

Figure 6 is a fragmentary perspective view 60 of the bottom of the body, showing a part of the mechanism for raising the rear wheels, and the locking means for holding the same in raised position.

Figure 7 is an elevation partly in section 65 of a part of the counter drive shaft and the clutch mechanism carried thereby.

Figure 8 is a perspective view of the shifting mechanism for operating the clutches.

Figure 9 is a side view of a part of the 70 bottom of the car body, showing the riding spring supported thereon, and the locking mechanism for holding same in operative position.

Figure 10 is a side elevation of one of the 75 band clutches.

Figure 11 is a front view of one of the expandible male clutch members.

Figure 12 is a perspective view of one 80 of the clutch wedge dogs.

Figure 13 is a perspective view of the clutch controlling lever.

Figure 14 is an end view of the trunnion journal box for the propeller shaft.

Figure 15 is a front view of the propeller 85 shaft support.

Figure 16 is a vertical sectional view of the stuffing box surrounding the axles where the latter penetrates the wall of the car body.

Figure 17 is a sectional view on line 90 17-17 of Figure 2.

Figure 18 is a perspective view of the lower end of the control lever for the wheel lifting mechanism.

Figure 19 is a perspective view of the locking dog carried by said lever.

Figure 20 is a horizontal sectional view in line 20-20 of Figure 2.

Figure 21 is a sectional view on line 100 21-21 of Figure 5.

Figure 22 is a sectional view on line 22-22 of Figure 6.

Figure 23 is a sectional view on line 23-23 of Figure 6, and

Figure 24 is a perspective view of the 105 bend, in the forward axle.

Referring to Figure 1 of the drawings, 1 designates a car body formed like a boat consisting of a floor 2 spaced from the bottom 2', said floor and bottom being curved forwardly and upwardly, a stern wall 3,

2

and side walls 4 and 5. Thus, is formed what may be termed a hollow bottom for the car body, constituting a water displacing element and forming a large part of the total displacement. Extending transversely of the body is the seat 6, preferably located midway between the ends thereof. To the rear of the seat and extending transversely of the car body and rotatably supported by means of the journal boxes 7 on the floor 2, is the rear axle 8, and located forward of the seat, and in parallelism with the rear axle and likewise rotatably supported by means of the journal boxes 9, on the floor, is the front axle 10. The front axle is formed at its ends with forwardly extending bends 11, lying normally in a horizontal plane and being bent downwardly at their extremities to form vertical knuckle bearings 12, said bearings rotatably fitting in the journal hubs 13 so as to form a fulcrum pivot for the transversely disposed front wheel stub axles or steering knuckles 14. Each stub axle is formed at its outwardly extending part with a wheel bearing or spindle 15, adapted to rotatably carry the usual automobile wheel 15' (details thereof not shown) and with an inwardly extending lever arm having pivotal connection 16 with a flexible cable 17, so that when said cable is pulled the wheel on the spindle may be bodily revolved in a horizontal plane to steer the car, said outwardly extending part also having a pivotal connection 18 with the cable 19.

35 Successively arranged to the rear of the rear axle, are the motor 20, the radiator 21 for the motor, and the propeller 22, the radiator and propeller being located outside the rear wall 3, and supported on the extension 40 23 of the hollow bottom. Centrally, lengthwise, the front axle which is tubular, is divided into two sections by the gap 24, (Fig. 4) the adjacent ends being joined together by the forwardly extending horizontal plate 45 25, having hinge connection 26 with said adjacent ends so as to swing in a vertical plane, said plate being cut away adjacent the gap to free the latter from obstruction. Firmly secured to the axle, one for each of 50 said sections, adjacent said gap, are the forwardly extending lever members 27, preferably of plate, and located in the plane of the return bends 11, so that each section may be swung upwardly independent of the other. In addition to the journals 9, each section has additional bearing (Fig. 16) in the stuffing box 28, secured to the side wall and surrounding the axle, each stuffing box comprising a packing chamber 29 and a 55 gland 30 threaded to be screwed into said chamber and engaging the packing whereby the joint between the axle and the wall is rendered leak proof. The plate 25 is resiliently connected to the plates 27, by the coil 60 springs 31, which latter are similar to the spring 31' shown in Figure 9, said coil springs functioning as ordinary leaf springs for vehicles. Thus, when in operation, the weight of the car body tends to separate the plates 25 and 27, whereby the springs are 70 brought into tension (Fig. 9). The plate 25 (Fig. 2) is held locked in horizontal position by means of the locking mechanism 32, said mechanism comprising a horizontally disposed sliding bar or bolt 33, slideable in the guides 34, and formed with a spear head tip 34', the shoulder 35 thereof engaging the upstanding rib 36 along the edge of said plate. It will be noted, that the plate 25, which is controlled substantially in the same manner as the plate 87 of the front axle, is normally slightly elevated from the floor 2 (Fig. 9) to afford room for it to fall out of engagement with the shoulder 35 as shown by dotted lines. This disengagement is effected by the weight of the wheels, which latter tend to sink when the car body is brought to rest on the surface of the water, whereby the bar 33 is rendered free to be slid in its guides out of the path of the plates 25. 80 Thus, when the bar is withdrawn as by means of its cable 37 the plate 25 is free to be swung upwardly by means of the cable 38, which latter has secure fastening at 38'. In order to, in part, counterbalance the weight of the wheels to facilitate raising them, the counter springs 39 are provided, said springs extending from the plates 27 to the post 40, the latter being best shown in 85 Figure 9 of the drawings.

90 As stated in the foregoing, the front axle 10 is tubular, (Fig. 24), the cables 17 and 19 extending from the stub axle 14 and respectively, over the pulleys 41 and 42 and through the interior of the tubular axle as 105 is best shown in Figure 5 of the drawings. The cables are continuous from one stub axle to the other and are parallel with and adjacent one another. Extending across the gap 24 and telescopically into the opposite ends of the tubular axle so as to be slideable longitudinally therein, is the shuttle sleeve 43, having centrally lengthwise a series of regularly spaced annular ribs 44 spaced to a pitch adapted to mesh with the teeth of the gear 45 mounted on the shaft 46, said shaft disposed coincident with the longitudinal axis of the car body, and inclined rearwardly and journaled in the journal supports 47 and 48. As shown in Figure 21, the cable 19 extends loosely through the sleeve while the cable 17 extends through said sleeve but is firmly secured therein by means of the set screw 49, so that when the sleeve is reciprocated by means of the gear 45 the stub axle 14 will be rotated upon the knuckle bearing 12, whereby the car is 110 steered.

115 As indicated in Figure 5, the floor 2 of the car body is sunken to accommodate the gear 120

45 and the journal supports 47 and 48. Journalized in the top of the column 50 and inclined rearwardly to a position adjacent the seat 6 is the steering column 51, said 5 column having additional journal supports 52 (Fig. 3) depending from the frame work of the car body. The steering column is formed of a tubular section 53 having mounted thereon a sheave wheel 54 and a 0 sprocket wheel 55, said sprocket wheel having operative chain connection 56' with the sprocket wheel 57" rigidly mounted on the shaft 46. The tubular section 53 of the steering column is formed to telescopically 15 receive a squared shank 56, which in turn carries the hand wheel 57 at its upper extremity. Thus, by turning the hand wheel the sleeve 43 may be reciprocated to steer the car. Rotating with the tubular section 20 53 and pivoted thereon so as to swing outwardly therefrom is the locking dog 57' adapted to engage the notch 58, of the squared shank 56, whereby the telescopic movement of said squared section may be 25 checked. Having swivel connection 59 in the inner end of the squared shank 56 and extending downwardly through the hollow of the tubular section 53 is the flexible cable 60, the purpose of which will be here- 30 inafter explained.

Referring now to Figure 3 of the drawings, 61 designates the driving shaft in connection with the motor, said shaft carrying the spur gear 62 meshing with the gear 63, 35 which in turn meshes with the gear 64, the latter meshing with the gear 65 mounted directly on the propeller shaft 66. Said propeller shaft being journalized in the journal box 67, said journal box being supported on 40 the trunnions 68 (Fig. 14). At its outer end the shaft carries the propeller 22 having its discharge side to the rear. Surrounding the propeller is the guard frame 69 suitably enclosed with wire screening as shown. The 45 guard frame is suitably braced by means of the tie rods 70 to the car body, and is formed at its top with the journal 71 wherein is swingingly supported the outstanding rudder 73, said rudder having journal support 72 50 in the body of the car. At its lower extremity, the rudder is formed with laterally extending opposite arms 74, each arm having pivotal connection respectively with the cables 75 and 76, whereby when said cables are 55 pulled the rudder will be caused to swing laterally.

Rigidly mounted on the motor shaft 61, is the miter gear 77 meshing with the gear 78, the latter rigidly mounted on the vertical 60 shaft 79, said shaft having journal support in the bracket 80 and the car body frame.

At its lower extremity the shaft rigidly carries the bevel gear 81, in mesh with the gear 82, the latter rigidly mounted on the 65 horizontal longitudinally disposed jack

shaft 83, said shaft carrying rigidly, at its forward end, the bevel gear 84.

The rear axle 8 is formed with rearwardly extending bends 85, the transverse portion thereof being tubular and cut away 70 midway between its ends to form two sections leaving a space for the insertion of the clutch mechanism 86. Each section has, in addition to journals 7, further journal support in the stuffing box 28, similar to the 75 forward axle 10. Further, each axle section is provided with plates 87 and 88, corresponding in effect to plates 25 and 27 of the axle 10, and being similarly connected by the riding spring 31, and provided with 80 a counter spring 39 attached to a post 40. As, however, the axle sections are more widely separated than those of axle 10, each pair of plates is provided respectively with a lifting cable 89 and 90, as distinguished 85 from the single cable 38 provided for lifting the front wheels. Likewise, each plate 87 is provided with individual locking mechanism 32 similar in every respect to that already described in the foregoing in 90 connection with axle 10, these mechanisms having, respectively, cable connections 37' and 37". Extending through the interior of each axle section is the drive shaft 91, the inner terminals thereof having adj- 95 acent journal supports 92, and the outer ends thereof extending through and beyond the axle section (Fig. 20) and having sprocket gear 93 thereat. Extending outwardly from the terminals of each of the bends, is a stub-shaft 94 (Fig. 17) disposed parallel with the axles, and rotatably carrying a rear traction wheel 95, said wheel having a sprocket 96 having chain connection 97 with the sprocket 93. Mounted loosely adjacent 100 the journal supports 92, one on each of the shafts 91, and oppositely disposed thereon are the female cone clutch members 97, (Fig. 7), adapted to receive the male clutch member 98 rigidly mounted on the shaft. 105 The male member of the clutches comprises a split ring 99, having web connection 100 with the hub, said connection being opposite the split 101, which latter is slightly tapered to receive the wedge 102 of the clutch sleeve 110 108, said sleeve being slidably mounted on the shaft 91. The sleeve is formed with an annular groove 104 adapted to receive the ring 105 of one of the arms 106, so that the sleeve may rotate in the bore of the ring. 115 The arms 106 extend forwardly and are firmly connected to the shifting shaft 107, said shaft being slidable in the guides 108 secured to the floor 2. Thus, when the shaft is shifted in one direction to force one of 120 the wedges into its respective clutch member to thereby expand it into frictional connection with the female member, the opposite wedge will thereby be withdrawn from the split of its clutch member. Ob- 125 130

viously, either clutch may thus be arbitrarily thrown into operation, or, by holding the shifting shaft in such position, as to disengage both wedges, be held in neutral position.

Secured on the shaft 91, one for each axle section, are the ordinary band brakes 109, (Fig. 10) said brakes being formed with the usual split strap band 110, having fulcrumed lever 111 pivoted on one end thereof and a tie bolt 112 connecting the opposite end of said band with said lever, whereby when said lever is pulled as by means of the cable 113, the strap band may be frictionally clamped to the friction disk 114 firmly secured to the shaft. A relatively stiff coil spring 115 connects the band with the floor 2 of the car to afford a resilient connection between the band and the car body. A separate spring 115' keeps the bands constantly in inoperative position. The floor 2 as shown in Figure 7 has suitable pits 116, to accommodate the clutches, and 117 to accommodate the brakes.

Having ball and socket connection 118 with the wall 4 of the car body and extending transversely across the latter forward and adjacent the hand wheel 57, is the clutch and locking mechanism controlling lever 119, said lever being provided with an upstanding loop 120, through which passes the cable 121 said cable having secured thereon one on either side of said loop, the stopping disks 122, so that when said lever is moved in a horizontal plane the cable will be pulled in either direction as the case may be. Extending horizontally directly beneath the lever 119 as at 123 and immediately adjacent thereto so as to be flexed downwardly when said lever is moved in a vertical plane is the cable 37. Pivottally mounted by means of the pivot 124 in elevated position relative to the floor 2, and supported on the latter by means of the standard 125, is the wheel lifting foot lever 126, the pivot 124 constituting a fulcrum therefor and the upper end of said lever having connection with the cable 38. At its lower end the lever is provided (Fig. 18) with a transversely extending pin 127 whereon is rotatably supported the latch dog 128 having and upwardly extending release lever 129 and a stop lug 130, said stop lug adapted to engage the edge of the lever 126 at 131 to restrict the upward movement of said dog, whereby it is held in the position shown in Fig. 4. A coil spring 132 holds the dog under stress in said position.

The cable system which is operated from the steering post and the levers 126 and 119, is best shown in Figure 3 of the drawings wherein, to render the various cables traceable from their source of operation to the mechanism which is designed to operate the cables, are diagrammatically illustrated in

perspective, all changes of direction in the cables such as return bends and the like, being taken care of by suitable rollers generally indicated in the drawings by spools such as indicated by 133 all of the spools 70 being shown of an equal size to keep the drawings clear, it being understood that rollers of various sizes and shapes may be substituted.

The rollers will be referred to in numbers 75 designated by R^1-R^2 , etc., so as to distinguish from the numbers used throughout the specification. The cable 60 connected with the squared shank 56 of the steering column extends to $R^1-R^2-R^3$, where it 80 is joined to the cables 113, one of said cables extending to R^4 to brake and the other extending to R^5 to brake.

Obviously, when the hand wheel is pulled outwardly the lever 111 of the brakes will 85 be operated to set the latter, by means of spring pressed dog 57 which will engage the notch 58 to hold the brakes set. To release the brakes, the finger piece of the dog is provided. For the purpose of operating the 90 rudder 73, the cables 75 and 76 (Figs. 3 and 5) are provided. These cables are fastened at 134, to the periphery of the sheave wheel 54, the cable 76 extending from the sheave to $R^6-R^7-R^8-R^9-R^{10}$ to rudder arm, 95 and the cable 75 from the opposite rudder arm to $R^{11}-R^{12}-R^{13}-R^{14}-R^{15}$ to sheave. It will be noted that the cables 75 and 76 are crossed between the sheave and R^6 and R^{15} , thereby causing the rudder to swing in 100 the same direction in which the hand wheel is turned, so that the rudder will assist in steering the car on land and constitute the sole steering medium on water. The cables 75 and 76 are provided with suitable stuffing 105 boxes 134', similar to the stuffing box 28 (Fig. 16). For the purpose of separating the locking mechanism, or in other words, withdrawing the bolts 33 of said mechanism to permit the wheels to be raised, the 110 cables 37 and 37' and 37'' are provided, the cable 37 extending from sliding bolt to $R^{16}-R^{17}-R^{18}-R^{19}-R^{20}-R^{21}-R^{22}$ where it is joined to the cables 37' and 37'', the cable 37' extending to the locking mechanism on one side of the car body and the cable 37'' extending to the locking mechanism on the opposite side of the car body. The cable 37 passes under the lever 119 immediately adjacent to its underside as shown in Figure 13 in the drawings, so that when 115 said lever is moved downwardly upon its pivot 118 it will flex the cable 37 as shown in dotted lines whereby said cable will be pulled at its point of attachment with the forward locking mechanism and also, the cable 37' and 37'' attached to the rear locking mechanism. The cable 37 passes under the lever 119 immediately adjacent to its underside as shown in Figure 13 in the drawings, so that when 120 said lever is moved downwardly upon its pivot 118 it will flex the cable 37 as shown in dotted lines whereby said cable will be pulled at its point of attachment with the forward locking mechanism and also, the cable 37' and 37'' attached to the rear locking mechanism.

For the purpose of sliding the shifting shaft 107 and thereby operate the clutches, the cable 121 is provided, this 125

130

cable as hereinbefore explained is provided with stop disks 122 so that when the lever 119 is reciprocated horizontally the cable may be pulled back and forth as desired.

5 The cable 121 extends from the lever 119 to R²³— to R²⁴— to R²⁵, to shaft 107, to R²⁶, to R²⁷— to R²⁸— to R²⁹ to lever 119. Thus, by moving the lever in a horizontal plane the clutches may be controlled and by 10 moving said lever vertically the locking mechanisms may be controlled. As shown by the arrows in Fig. 3, of the drawings the gear 82 viewed from the front of the car runs clockwise so that the rear right- 15 hand wheel facing the car will run in reverse direction, and the left hand wheel will run forward when the respective clutches are operated.

For the purpose of raising the wheels the 20 cables 38—89 and 90 are provided. The cable 38 extends from the plate 25 of the front axle to the foot lever 126, while the cable 89 extends from the plate 88 adjacent the wall 5 of the car body to

25 R³⁰—R³¹—R³²—R³³ to foot lever 126 and the cable 90, from the plate 25 adjacent the wall 4, to R³⁴—R³⁵—R³²—R³³ to foot lever. After entering the water, the driver engages the dog 128, with his foot (Fig. 4) to bring 30 it into locking engagement with the down-turned hook 135 secured to the floor 2 as shown in dotted lines. To release the wheels, the release lever 129 is forced forward, whereby the hook and dog are disengaged.

35 In Figure 1 of the drawings A designates the water, it being noted that the propeller is located above same. To start the motor the propeller may be turned and to stop same the usual mechanism employed in 40 automobiles is utilized but not shown in the drawings. The wheels may be said to be offset relative to the tubular parts of the axles, each axle section constituting a U-shaped fulcrumed lever, having a wheel at 45 one terminal and attached to the spring 31 at the other.

I claim:

1. A sport car of the class described, comprising a body formed to float, means including a power unit for propelling said body, supporting wheels for supporting said body on land pivotally mounted to be swingable bodily upward when the body is afloat to a position above the water line, and to 55 swing bodily downward by gravity to a predetermined degree when the body is afloat, releasable locking means including releasing means therefor, extending into engagement with a part of the pivotal mounting of said wheels to check upward movement of the latter and render said releasing means inoperable, said releasing means being rendered operable by the downward swinging movement of said wheels.

65 2. A car for use on land and water, com-

prising a body constructed to float, a propeller above the water line, a rudder to the rear of the propeller, a power unit operatively connected with the propeller, a front and a rear rotatably mounted axle extending transversely of the car body, the outer ends of said axles carrying wheels and being offset laterally, the front axle offset in a forward direction and the rear axle in a rearward direction, the offset ends of the front axle being pivoted to constitute fulcrumed steering knuckles, releasable locking means for holding the axles against rotation, means for releasing said locking means, means for simultaneously rotating said axles to raise the wheels, and steering mechanism operatively connected with said rudder and steering knuckles and extending to and including a hand wheel at the driver's position, said mechanism including flexible connections extending from said knuckles approximately through the axis of rotation of the axle.

3. In a car for use on land and water the combination with a body capable of floating and means for propelling same when it is afloat, said means including a propeller and a power unit, of a front and rear axle each having two wheels for supporting the body, said axles being rotatably mounted transversely of the body, and having their wheels offset so that the latter will swing bodily upward when the axles are rotated, means for rotating the axles and holding same in upswung position, means for steering the front wheels, and clutch mechanism operatively connected with said power unit and the rear wheels, said mechanism including oppositely revoluble clutches, one for each wheel and means for arbitrarily rendering operative either of said clutches.

4. A vehicle of the class described, comprising a body capable of floating and means for propelling same, said means including a propeller above the water line, of a front and rear axle each carrying two supporting wheels one on each outer end thereof, for supporting said body, each of said axles being formed of two simultaneously rotatable sections, each section constituting a fulcrumed U-shaped lever, the axis of rotation of the axle being coincident with the fulcrum thereof, an arm one for each fulcrumed lever, pivoted in the fulcrum thereof, and extending spacedly in vertical alinement under the inner portion of the fulcrumed lever, a resilient connection between said arm and said inner portion, means for simultaneously rotating all of said sections to raise the wheels, releasable holding means engaging with said arm to hold it in fixed relation to said body, and means for releasing said holding means.

In testimony whereof I affix my signature.

CLIFFORD J. ZWICKEY.
